UNITED STATES PATENT OFFICE.

CHARLES E. MARTIN, OF MANSFIELD, OHIO.

REVOLUBLE FILLER-PIPE CONNECTION.

1,199,198.

Specification of Letters Patent. Patented Sept. 26, 1916.

Application filed February 21, 1916. Serial No. 79,540.

To all whom it may concern:

Be it known that I, CHARLES E. MARTIN, a citizen of the United States of America, residing at Mansfield, in the county of Rich- 5 land and State of Ohio, have invented cer- tain new and useful Improvements in Rev- oluble Filler-Pipe Connections, of which the following is a specification.

This invention relates to a revoluble filler 10 pipe connection for silos or the like.

The primary object of this invention is to provide a filler pipe connection for silos that can be easily and conveniently revolved around the body thereof to any point de- 15 sired, so that connection can be made be- tween the filler pipe connection and the filler pipe of an ensilage cutter or the like at any point around the silo that is most accessible or easy of approach for placing the ensilage 20 cutter or the like.

A further object is to provide a filler pipe connection for silos or the like that can be revolved to any point around the body thereof and at all points direct and conduct 25 the ensilage from the ensilage cutter through a central opening at the top into the silo.

Another object is to provide a simple and an efficient means of mounting for rotation in the central opening of the silo roof one 30 end of a filler pipe connection, the free end thereof being arranged and formed to travel around the body of the silo when the mounted end is rotated.

A further object is to provide a means of 35 rotatably mounting the filler pipe connection which also affords facilities for clamping the ends of the sections of the roof.

I attain these and other objects by the mechanism illustrated in the accompanying 40 drawing, in which:

Figure 1 is an elevation of a fragment of a silo body, having a silo top mounted thereon, and a side elevation of the revoluble filler pipe connection showing it applied thereto. 45 Fig. 2 is a sectional view of Fig. 1, taken on the line X-X. Fig. 3 is a sectional view of the filler pipe connection taken on the line 2-2 of Fig. 1. Fig. 4 is a vertical central section of Fig. 1 showing the assembly of 50 the parts, a fragment of the silo roof, also two sections of the ensilage conductor pipe. Fig. 5 is a cross sectional view of Fig. 4 on the line 0-0.

In the drawings, reference numeral 1 55 represents a fragment of a silo body, 2 and 3 parts of a conventional silo roof. Part 3 is

provided with a central opening 4 and a collar 5 having a beaded upper portion 6 and a flanged lower portion 7 which extends over and around the upper ends of the sections forming a central opening in the part 3. A band ring 8 telescopes the inner periphery 7 of the collar 5 and the flange 9 thereof is preferably made integral therewith, extending underneath and around the upper ends of the sections, forming a central opening in the part 3. The upper ends of the sections forming the part 3 are interposed between the flanges 7 and 9 and the flanges and upper ends of the sections are 60 clamped together holding the collar 5 and ring 8 in a vertical position with respect to the part 3 of the silo. L shaped brackets 11 are fastened at predetermined points to the inner periphery of the ring 8 so as to leave 65 their free bent ends extending inwardly toward the center of the opening in the part 3 of the silo roof. An angular ring 12 rests upon the free ends of the L shaped brackets; it is attached to and supported thereby pref- 70 erably in a central position with reference to the opening in the part 3 of the silo roof. In order to rigidly support the angular ring 12, the L shape brackets are provided with 75 braces 13 which are fastened to the part 3 of the silo roof and their free ends extend underneath and are secured to the free ends of the L shape brackets. Bolts 10 secure the braces 13 to the band ring 8 at one end and the opposite ends of the braces are secured 80 by the bolt 10' to the free ends of bracket 11.

Vertical standards 14 are secured to the inner periphery of the collar 5 and their lower ends are formed L shape and ar- 85 ranged and so located as to aline with the brackets 11, but spaced apart therefrom. A hood 15 having a central opening is mounted upon the upper portion of the standards and is provided with an upstanding flange 16 which surrounds the central opening. 90 Bolts 17 pass through apertures in the ends of the vertical standards and the bracket 11, and when said bolts are manipulated to tighten them, the flanges 7 are drawn to 95 and forced in frictional contact with the top of the ends of the sections forming the part 3 of the roof, and simultaneously therewith the flanges 9 are drawn to and forced in frictional contact with the bottom of the ends of the sections forming the 100 part 3 of the silo roof, thereby securing firmly and adjustably clamping the inter- 105 110

posed ends of the sections of the part 3 of the silo roof between said flanges and rigidly clamping the collar 5 and the band ring 8 together. The space 18 between the 5 brackets 11 and the L shaped ends of the supports 14 permit of their adjustment toward each other to insure efficient and rigid clamping contact or effect.

The filler pipe revoluble connection 19 is 10 provided with an angular ring 20 which is preferably located and secured to the filler pipe connection at a point above the end 21. The angular ring 20 rests upon and is supported upon the angular ring 12 thereby 15 supporting for rotation the filler pipe connection 19 upon what might be aptly termed a "turn-table" mechanism. The free open end 22 of the filler pipe connection is arranged and formed to lie spaced apart from 20 the exterior of the silo body. A flange coupling 23 is provided on the end of the filler pipe connection.

Reference numeral 24 represents a fragment of an ordinary filler pipe having a 25 flange coupling 25 attached thereto, the opposite end (not shown) being adapted to be connected to an ensilage cutter or the like.

A sliding bracket shoe 26 is attached to the free end 21 of the filler pipe connection 30 and its feet 27 are adapted to slide around the exterior of the silo body maintaining the free end of the filler pipe connection at a predetermined distance from the silo body as it is being revolved around said silo body. 35 Braces 28 are provided to strengthen the filler pipe connection at the point where it is curved.

Reference numeral 30 represents sections of a conductor pipe. 40 The operation of the rotatable pipe filler connection is as follows; to wit: The ensilage cutter or the like is first located at a point around the silo that is the most accessible or easy to approach, the user then 45 mounts the ladder 29 and revolves the filler pipe connection until it is in close proximity to the ladder and convenient to the user; the filler pipe 21 is then connected to the revoluble filler pipe connection 50 through the medium of the flange couplings and the filler pipe connection carrying the filler pipe is then revolved to a point where it can be easily and conveniently attached to the ensilage cutter, thereby obviating the 55 necessity of using a separate ladder or providing a suitable place to erect it.

What is claimed is:

1. In combination with a silo and a silo

roof, a filler pipe connection, means to mount one end thereof for rotation over a central opening in the roof, the opposite end being arranged and adapted to travel around the silo when the mounted end of the filler pipe connection is revolved.

2. In combination, a silo, a silo roof provided with a central opening, a filler pipe connection, means to mount one end of the filler pipe for rotation in the central opening of the roof, the free portion of the filler pipe being formed so that its end will lie adjacent to, but spaced apart from the silo, and means to slidably maintain the free end of the filler pipe connection in spaced relation to the silo when it is revolved.

3. In a revoluble filler pipe for silos, a silo roof provided with a central opening, means to mount one end of the filler pipe for rotation in said opening, the opposite end being bent to clear said roof and lie adjacent to the silo, and means attached to said last mentioned end to slidably contact with the silo and maintain said end a predetermined distance from said silo during the operation of rotating the mounted end 85 of the filler pipe.

4. In a revoluble device for filling silos, a silo roof having a central opening, a filler pipe, a ring and means to support same in said opening, a ring fitted adjacent to one end of the filler pipe and adapted to coöperate with the first mentioned ring to movably support said end for rotation in the opening in the roof, means to slidably support the free end of the filler pipe spaced 95 apart from the exterior of the silo.

5. In a revoluble device for filling silos, a silo roof having a central opening, a filler pipe, a ring and means to support same in said opening, a ring fitted adjacent to one end of the filler pipe and adapted to coöperate with the first mentioned ring to movably support said end for rotation in the opening in the roof, means to slidably support the free end of the filler pipe spaced 100 apart from the exterior of the silo, said free end of the filler pipe being adapted to be moved around the exterior of the silo to any predetermined point.

In testimony whereof I affix my signature.

CHARLES E. MARTIN.
